DESIGN FOR A GOOD LUCK CHARM OR SIMILAR ARTICLE

Charles H. McArthur, New York, N. Y.

Application February 2, 1937, Serial No. 67,403

Term of patent 7 years

To all whom it may concern:

Be it known that I, Charles H. McArthur, a citizen of the United States, residing at 310 East 44th Street, in the city, county, and State of New York, have invented a new, original, and ornamental Design for a Good Luck Charm or Similar Article, of which the following is a specification, reference being had to the accompanying drawing, forming part thereof, in which Fig. 1 is a view in elevation of a good luck charm showing my new design, and Fig. 2 is a sectional view on line 2—2 of the charm shown in Fig. 1.

I claim:

The ornamental design for a good luck charm or similar article substantially as shown.

CHARLES H. McARTHUR.
